(57) **CLAIM**

The ornamental design for a front door casing for a vehicle, as shown and described.

DESCRIPTION

FIG. 1 is a front right elevated perspective view of a front door casing for a vehicle according to the present invention.

FIG. 2 is a front right perspective view thereof.

FIG. 3 is a rear left elevated perspective view thereof.

FIG. 4 is a rear left perspective view thereof.

FIG. 5 is a front view thereof.

FIG. 6 is a rear view thereof.

FIG. 7 is a right side view thereof.

FIG. 8 is a left side view thereof.

FIG. 9 is a top view thereof; and,

FIG. 10 is a bottom view thereof.

The invention contemplates a mirror image door casing for the opposite side of the vehicle.
